(57) **CLAIM**

I claim the ornamental design for a vehicle module, as shown and described.

DESCRIPTION

FIG. 1 is a front bottom perspective view of one embodiment of a vehicle module of the present disclosure;

FIG. 2 is a front elevational view of the vehicle module of FIG. 1;

FIG. 3 is a rear elevational view of the vehicle module of FIG. 1;

FIG. 4 is a side elevational view of the vehicle module of FIG. 1;

FIG. 5 is a top plan view of the vehicle module of FIG. 1; and, FIG. 6 is a bottom plan view of the vehicle module of FIG. 1. In the drawings, the broken lines in the figures depict portions of the article that form no part of the claimed design.
